United States Patent Office

Des. 230,810
Patented Mar. 19, 1974

230,810

SERVICE TRAY

James J. Ryan, Jr., % George Wm. Lias,
16 E. Broad St., Columbus, Ohio 43215

Filed Nov. 27, 1972, Ser. No. 309,937

Term of patent 14 years

Int. Cl. D7—99

U.S. Cl. D7—27

Fig. 1

Fig. 2

Fig. 3

Fig. 4

Fig. 5

FIG. 1 is a perspective view of a service tray illustrating my new design;

FIG. 2 is a perspective view thereof from the side opposite to FIG. 1;

FIG. 3 is a top plan view thereof;

FIG. 4 is a bottom plan view thereof; and

FIG. 5 is a side elevational view thereof.

I claim:

The ornamental design for a service tray, substantially as shown.
